MOVING PICTURE PROJECTING MACHINE

Antoine Heurtier, Saint-Etienne, France

Application June 2, 1939, Serial No. 277,091
In France June 10, 1938

3 Claims. (Cl. 271—2.3)

My invention relates to an improved moving picture projecting machine adapted to operate with cinematograph film strips of different widths, viz 8 millimeters, 9.5 millimeters and 16 millimeters.

It is known that the three conventional types of films known as 8, 9.5 and 16 millimeter films differ from each other not only by their width, but also by the shape and the location of their driving perforations. The 8 millimeter film is perforated on one side only, the 16 millimeter film on both sides, while the 9.5 millimeter film is provided with transverse slits located between the successive pictures. The height of each picture also varies and the elementary motion of the film is therefore to be varied.

A first object of my invention is to provide a machine wherein the gearing controlling the step-by-step motion of the film may easily be adjusted to the dimensions and perforations thereof.

A further object of my invention is to provide an apparatus comprising a number of film driving sprockets with means to bring into action the one corresponding to the film projected.

In the annexed drawings:

Fig. 1 is a general side view of a machine according to my invention.

Fig. 2 is an end view of the rotatable film driving member.

Fig. 3 is a longitudinal section thereof.

Fig. 4 is a partial transverse sectional view showing the film advancing mechanism and its controlling gear.

Fig. 5 is a longitudinal section corresponding to Fig. 4.

Fig. 6 is an external side view showing the controlling device for the motion of the film advancing mechanism.

The machine illustrated comprises (Fig. 1) a projecting apparatus proper 1, a system of lenses 2, a film advancing mechanism generally referenced 3, and two sprocket devices generally referenced 4, these latter devices being supported by a frame 5 which carries the usual film reels, not shown.

Each sprocket device (Figs. 2 and 3) comprises an inner driving shaft 6 rotatably supported by a cylindrical bearing 7 fixed to frame 5, the said shaft 6 being continuously driven by means not shown. Bearing 7 forms a pivot rotatably carrying a circular plate 8 having an outer cover 9 and rotatably supporting three spindles 10. Shaft 6 terminates short of cover 9 and carries 55 a pinion 11 which meshes with gear wheels 12

keyed on spindles 10. The latter project through cover 9, as shown, and support film sprockets 13 each adapted to drive a determined type of film. Plate 8 has a hub 14 having a radial bore 15 housing a ball 16 pressed inwardly against bearing 7 by a spring 17 and bearing 7 has three corresponding depressions by means of which plate 8 may be elastically locked at three equidistant angular positions about the axis of shaft 6. Cover 9 supports loose film rollers 18, as shown.

Cover 9 also carries, coaxially with respect to shaft 6, a screw 19 forming a pivot for a star-shaped member 20 having three tails or branches projecting between the successive sprockets 13 18 (Fig. 2). Member 20 is normally retained at the proper angular position about screw 19, with respect to plate 8, by a ball 21 urged by a spring 22 into a depression provided on the inner end face of the said member. A milled screw 23 20 closes a bore 24 adapted to house the head of screw 19 and serves as a knob to rotate member 20.

As shown in Fig. 1 the film strip 25 is passed over the uppermost sprocket of the upper sprocket device and over the lowermost sprocket of the lower sprocket device and it is retained on each of the said sprockets by the corresponding central star-shaped member 20 and by the idlers 18. It will be easily understood that in a given 30 device plate 8 may be rotated at will to bring into active position the desired sprocket, i. e. the one corresponding to the type of film to be dealt with. It is also clear that member 20 can be rotated on plate 8 through a limited angle, 35 which facilitates disposing the film strip as required before the projection without scratching the same on the driving teeth of the corresponding sprocket, the said member being thereafter returned to its normal position. 40

Member 20 is grooved as shown at 26 (Fig. 2) to accommodate the teeth of the sprockets and there is provided an abutment 27 to limit the opening angle of the said member. The latter is shown in Fig. 2 at the disengaged or opened 45 position.

The film advancing mechanism (Figs. 4 and 5) comprises a continuously rotating shaft 28 driven by means not shown, the said shaft carrying three cams 29 within a cylindrical casing 30. 50 The latter slidably houses a piston-like member or slide 31 prevented from rotating by a nose 32 engaging a longitudinal groove 33 in casing 30. Slide 31 is integral with a hollow tail 34 having an external screw-thread 35 which screws 55

into the bore 36 of an actuating member 37 driven through the end wall of casing 30 and pressed against the same by a spring 38 acting on slide 31 co-axially with respect to the same.

5 Member 35 carries a ball bearing 39 supporting shaft 28.

It will be readily grasped that when member 37 is rotated slide 31 is axially displaced within casing 30.

10 Slide 31 has a transverse elongated opening or slit 40 forming a guide for a flat lever 41. The latter has an enlarged central portion provided with a rectangular opening 42 (Fig. 4) through which cams 29 are passed and it is urged upwardly against the same by a spring 43. Lever 41 has also near its end an elongated opening 44 through which is passed a rod 45 carried by an arm 46 adjustably fixed on a lever 47 which is rotatable about a circular projection 48 (Fig. 15

15 20 5) co-axial with shaft 28. Lever 47 carries an abutment 49 (Fig. 4) which bears against an adjusting screw 50 under the action of a spring 51 downwardly acting on lever 47. The right end of lever 41 is urged upwardly by an additional spring 52 which prevents noise due to transverse play of rod 45 within opening 44.

25 Lever 41 carries at its left end teeth 53 adapted to advance the film 28 as it will be more fully explained below.

30 The above-described member 37 is provided with three radial grooves 54 (Fig. 6) adapted to accommodate a finger 55 (Figs. 5 and 6) carried by a knob 56 fixed to the end of a rod 57 the other end of which is formed as a piston 58 urged 35 by a spring 59 within casing 30. Shaft 28 carries a cup-shaped member 60 which rotates close to the outer end face of member 37 thus preventing finger 55 from being withdrawn from grooves 54 except when the angular position 40 of shaft 28 is such that a notch 61 provided in the said cup-shaped member 60 is located in front of finger 55. Since member 60 has but one notch, it will easily be grasped that member 37 can only be rotated when shaft 28 is at standstill at a 45 determined angular position permitting finger 55 to be disengaged by pulling knob 56.

It will be understood that when member 37 is rotated, slide 31 is moved axially within casing 30, together with lever 41. For each of the 50 three angular positions of member 37 corresponding to the three grooves 54, lever 41 is thus positioned in the plane of one of cams 29 and is

given a determined oscillating motion corresponding to a determined type of film strip. The lateral displacement of lever 41 is also such that for each position of member 37 the appropriate tooth or teeth 53 are so positioned as to cooperate with the film strip. In the example illustrated, lever 41 is flat and carries three teeth 53 in the same vertical plane. For a 16 millimeter film teeth 53 only act on one row of lateral perforations, which is without inconvenience. 10 For an 8 millimeter film they act on the single lateral row of perforations provided in such film strips, and for a 9.5 millimeter film they cooperate with the central slits provided between the successive pictures.

15 It will also be understood that the cup-shaped member 60 is so adjusted on shaft 28 that finger 55 can only be disengaged when lever 41 bears on such a part of cams 29 that it may be slid from any cam to another one without difficulty, i. e., 20 on a part of cams 29 where the radius is the same for the three cams.

I claim:

1. In a moving picture projecting machine adapted to operate with several types of film strips, film driving means comprising a continuously rotating shaft; a plate rotatable co-axially with said shaft; a pinion at the end of said shaft; spindles rotatably carried by said plate; pinions on said spindles in mesh with said first-named 30 pinion; sprockets keyed on said spindles, each of said sprockets being adapted to a type of film strip; means to guide a film strip in engaging relation with each of said sprockets; and means to retain said plate in a number of positions corresponding to the active position of each of said 35 sprockets.

2. In film driving means as claimed in claim 1, said guiding means comprising a member secured on said plate in co-axial relation with the 40 same, said member being formed with extensions extending close to each of said sprockets, each of said extensions having grooves to accommodate the teeth of said sprockets.

3. In film driving means as claimed in claim 1, 45 said guiding means comprising a member secured on said plate in co-axial relation with the same, said member being formed with extensions adapted to extend close to each of said sprockets; and means to displace angularly said member 50 with respect to said plate.

ANTOINE HEURTIER.
